J. R. REYNOLDS.

SIGNATURE HOLDING ARM FOR BOOK SEWING MACHINES.

(Application filed May 20, 1901.)

(No Model.)

UNITED STATES PATENT OFFICE.

JOHN R. REYNOLDS, OF HARTFORD, CONNECTICUT, ASSIGNOR TO THE
SMYTH MANUFACTURING COMPANY, OF SAME PLACE.

SIGNATURE-HOLDING ARM FOR BOOK-SEWING MACHINES.

SPECIFICATION forming part of Letters Patent No. 681,509, dated August 27, 1901.

Application filed May 20, 1901. Serial No. 61,021. (No model.)

To all whom it may concern:

Be it known that I, JOHN R. REYNOLDS, a citizen of the United States, residing at Hartford, in the county of Hartford and State of Connecticut, have invented an Improvement 5 in Signature-Holding Arms for Book-Sewing Machines, of which the following is a specification.

My present invention is an improvement 10 upon the device patented to me June 19, 1887, No. 366,793, and also upon the device patented to myself and A. I. Jacobs, September 2, 1890, No. 435,611.

In book-sewing machines sheet or signature 15 holding bars have been arranged about a vertical shaft and devices have been employed for raising and lowering these bars and turning the same progressively, so that the signatures laid successively upon the bars are 20 presented one at a time to the sewing mechanism. These sheet or signature holding bars have projected radially at spaced-apart intervals from a head movable upon the vertical shaft, and associated with these bars 25 there has been a series of perforators and devices for moving the same vertically, and by this means holes were made through the fold of the signatures or sheets for the entrance of the curved sewing-needles. Heretofore the 30 devices employed for connecting these signature or sheet holding bars to the head have not been fully operative. These bars are liable because of their length and their quick up-and-down and swinging movement to sag 35 at the outer or free end, and screws employed to level the bars have had a bearing upon the edges of thin plates fastened upon the respective sides of the bar and between which were located the mechanism and the series of perforators. The action of these screws against 40 the narrow edges of the plates has been to bend and crush and otherwise mar the plates, and at the same time because of lack of structure and material it has been difficult to properly support the plates or hold the same 45 continuously in the desired position.

In my present invention the structure of the plate has been so changed and modified and the relation thereto of the thin side plates 50 so modified that the devices employed are adapted to bear upon a solid and integral por-

tion of the main bar, and in combination with such structure I employ novel devices for connecting the bar to the head and for holding and moving the leveling devices, so that the rapid 55 movements of the bar and adjacent parts do not tend to loosen the said devices or lessen the tension or hold thereof upon the bars.

In the drawings, Figure 1 is an elevation and partial section representing my present 60 improvement. Fig. 2 is an inverted sectional plan at the line $x-x$ of Fig. 1, Fig. 3 is an elevation at the supported end of the sheet-holding bar alone, and Fig. 4 is a partial inverted sectional plan representing a form of 65 my invention.

In this art the vertical shaft c , the head vertically movable upon the shaft c , the yoke 8, the clamping-nut 11 and devices adapted to engage the yoke 8 for vertically moving the 70 head, the sheet-holding bar e , the thin side plates 4, riveted thereto, are well known, as are also the range or series of perforators 2, the bar 6, to which they are connected by screws 7, the reciprocating bar 10, which, with 75 the bar 6, is between the plates 4, and the cam-slots 9 in the bar 10, by which with the screws passing through the plates 4 and a longitudinally-reciprocating movement of the bar 10 said parts are adapted to raise and lower the 80 said bar and the connecting-bar 6 and the series of perforators 2.

In my improvement the head comprises the sleeve a and integral disk 5, the flanged disk 3 surrounding the sleeve a and vertically 85 movable, said disks being horizontally disposed and spaced apart. Each sheet-holding bar e is received between the disks 3 5, and screws 15 form guides for the disk 3 and hold the disks together, clamping the bars e between. A locking-pin 12 passes through the disk 3 into a notch in the upper edge of the bar e , and steady-pins 13 are located in the upper surface of the disk 5 and come at opposite sides of the bar e , so that in connecting the bars e to the head the same are slipped 95 between the steady-pins 13 into the recess formed between the disks and the sleeve a , the disks are drawn together, and the locking-pins 12 come down to place. Each sheet-holding bar e is provided with a foot part e' integral therewith, the bars at this place be- 100

ing transversely of a surface width appreciably greater than the measurements of the head between the under surface of the disk 3 and the under surface of the disk 5, so that 5 as each bar *e* is in place its foot portion *e'* sets up adjacent to the face or periphery of the disk 5 and extends below the same, as hereinafter set forth. There is therefore not only the support of the horizontal faces of 10 the disks 3 5, but the vertical face of the sleeve *a*. The side plates 4, connected to the bar *e* by the rivets 1, have their vertical back edges placed a slight distance away from the contacting edge of the foot part *e'* with the 15 disk 5. The under surface of the flanged disk 3 is radially slotted to receive the upper edges of the signature-holding bars *e*.

In the preferred form of my invention (shown in Figs. 1 to 3, inclusive) I employ 20 cam-disks *h*, secured to and upon the under side of the disk 5 by screws *i*. These cam-disks agree in number with the number of the signature-holding bars *e*, and the foot parts *e'* are of sufficient depth to extend across 25 the peripheral faces of the said cam-disks and to bear thereon. The screws *i* are in line with the bars *e*, and the said cam-disks *h* are provided with holes *l*, radially placed and spaced apart, extending into the periphery 30 for engagement by a spanner or key employed to turn the cam-disks against the foot part *e'* of the bar *e* for applying force for elevating the outer end thereof and holding the bar in place. It will be noticed from the drawings 35 that the entire edge faces of the foot parts *e'* bear upon the peripheral faces of the cam-disks, thus providing an ample bearing-surface, lessening the possibility of injury to parts.

40 In the modified form of the invention (shown in Fig. 4) screws *b*, agreeing in number with the number of the signature or sheet holding bars, occupy radial positions in the head. I prefer to employ four of such screws.

45 The head portions of the screws are in openings in the annular rib *a'* and the threaded portions of the screws in interiorly-threaded openings in the sleeve of the head, the screws by preference being provided with transverse 50 holes to receive a small rod by which they are turned, and beneath the flange 5 and between the pairs of screws I employ arc-pieces *d*. The ends of these arc-pieces are notched to receive the curved surfaces of the screws *b*, 55 and I employ tension-screws 14, passing through the annular rib *a'* against the outer surfaces of the arc-pieces, the movement of which forces the arc-pieces toward the screws *b* to create a friction and a holding function,

60 which prevents vibration or accident turning the screws *b*. The pressure exerted upon the screws *b* by the arc-pieces *d* may be readily regulated by the screws 14. It will be noticed, especially by reference to Fig. 4, 65 that the flat faces of the heads of the screws *b* rest against the edges of the foot parts *e'* of the sheet-holding bars, so that the force

exerted upon the bars by the screws is received upon the full width of the bars and upon so much of the edges of the bars as 70 agrees with the diameter of the screw-heads, so that an ample bearing-surface is provided which prevents injury to each signature-holding bar when tension is applied to force the bar away from the annular 75 rib *a'* and disk 5, so that its outer end may be raised sufficiently to cause its upper edge to be horizontal and true. It will also be apparent that the structures are alike in function and that no pressure whatsoever is 80 brought upon the rear edges of the narrow side plates 4 by the bearing or operation of either device, as said edges are placed at a short distance away from the edge of the foot-pieces *e'*, against which the heads of the 85 screws bear.

I claim as my invention—

1. In a signature-holding arm for book-sewing machines, the combination with a head and its disks 3 and 5, of the sheet-holding 90 bar *e* adapted to be received against the head between the disks and having a foot part *e'* extending over and beyond the periphery of the lower disk, and an adjustable device connected to the head and having a flat face 95 adapted to bear against the edge of the foot part for effecting and maintaining the desired position of the sheet-holding bar *e*, substantially as set forth.

2. In a signature-holding arm for book-sewing machines, the combination with the head, its disks 3 and 5, of the sheet-holding bar *e* having a foot part *e'* and adapted to be received against the head between the disks with the foot part extending over and beyond 105 the periphery of the lower disk and rotatable devices having flat faces bearing upon the edge of the foot part of the sheet-holding bar, substantially as and for the purposes set forth.

3. In a signature-holding arm for book-sewing machines, the combination with the head, its disks 3 and 5, of the sheet-holding bars *e* each having a foot part *e'* and adapted to be received against the head between the disks with the foot part extending over and 115 beyond the periphery of the lower disk, and locking-pins 12 passing through the upper disk 3 into the upper edges of the sheet-holding bars and steady-pins 13 rising from the surface of the lower disk 5 and coming at opposite sides of the sheet-holding bars *e* and rotatable devices agreeing in number with the number of the sheet-holding bars and coming against the edges of the foot parts of the sheet-holding bars, substantially as and 120 for the purposes set forth.

4. In a signature-holding arm for book-sewing machines, the combination with the head, its disks 3 and 5, of the sheet-holding bars *e* each having a foot part *e'* and adapted 130 to be received against the head between the disks with the foot part extending over and beyond the periphery of the lower disk, and locking-pins 12 passing through the upper

disk 3 into the upper edges of the sheet-holding bars, and steady-pins 13 rising from the surface of the lower disk 5 and coming at opposite sides of the sheet-holding bars *e*, cam-disks agreeing in number with the number of the sheet-holding bars and having peripheral faces coming against the edges of the foot parts of the sheet-holding bars, and screws

for securing the cam-disks to and against the under face of the disk 5, substantially as set forth.

Signed by me this 15th day of May, 1901.
JOHN R. REYNOLDS.
